(76) Inventor: **John Templeman**

John St. Johnman
Setters Patent

The structure referred to in these Setters Patent are working part of the
bridge containing a description in the name of the Inventor St. Johnman
himself of his improvements to the construction of bridges....

Method of making the chains for chain bridges of iron are made round iron
wire three of flat iron, lay with me two three quarters of an inch thick and
nick and half wide to be an inch thick at both ends six inches in length
each end. Then take the bars of iron eight of an inch thick and an inch
and an half wide to be four eighths of an inch thick at each end and six
inches in length on each end. Then punch corresponding holes in all the
bars about one inch from the end and when they are about three quarters
of an inch open them flat and when so done they are to
be same size and perfectly even then make holes to fit them; there put
the bars through and vice versa. By this means the chain will consist
of one single bar link and one double bar link alternately unless it is for
force since then all double bar links will be. In that case all the bars
must be of an equal thickness. Before the bars are twisted together holes
of about a quarter iron wire diameter should be punched through the
middle of the two bars to correspond and then a piece of iron three quarters
of an inch thick and nickel and half iron should be punched
through and then placed between the two thin bars and twisted to app
ositely the additional thickness of the iron wire. to compensate for the
loss of strength by having the holes through them. The of course
in circumstances requires this iron ought to be made on fine
spun and a more rope or hawser rope are to
be made by slightly twisting iron or iron
then and
after forming them into strands then lay them together like a
second set of strands can be made and laid to the others
and if that open then should be
hollow parts

in my improvements in the construction of Bridges by these improvements
the beams and iron & bolts &c &c & to construct a substantial bridge by
bracing, in which is to be placed the two stones, or for cast stone
piers or stone masonry. Then here follows the other mentioned claims are
here also my property claimed the same to be placed by laying each timber
with timber & and bracing up in that way a sufficient height
and then putting the plank and railing. But the best way is to make
there a stone section of timber bracing, back and to have each section come
out with the rest a stone of timber back opposite on the opposite, that the
strain, in the case the post should be lost long enough to recover the stone
joints of the post to the floor and the railing which will connect the whole
together with much firmness. These plans will answer if lost section in
some degree corresponding with the ^{course of the} rope or chain. Another of my im-
provements in the construction of Bridges which will be cheap and answer
for all parts of the hundred, but in length it will not my support from chains
or ropes. In this case uprights are set on the abutments and piers, and
from the top of the upright come down flat bar iron or wood, say white
tak plank of about four inches thick and six inches wide. These bars
are to be of various lengths and to be connected with the flooring of the
bridge in a firm manner by bolts to large timber by setting. Middle up-
right bars this sort of bridge can be covered and when the bracing is
of wood holes are to be bored about the timber, so as to make big enough
to receive a bolt of one inch in diameter and then run to the sides of the
plank at the corners and plates of iron of about half an inch thick
and ten feet long to give strength to the wood where the bolts go. The
iron and wooden braces above described I apply to James Finlays
Chain bridge for the purpose of affording steadiness and solidity to the
pier & wall or additional strength in the middle support of small brid-
ges as for the support of an old bridge, my improvement is to have a
sort of wooden chain to be made with some plates on the ends with holes
through them and to be put together like the above mentioned flat bar
iron chain. In such case the wood must be of a size to meet the degree
of strain required. Another of my improvements applicable to bridges

The bridge of one Span is to have a plurality of parallel timber in the bridge running lengthwise (under my direction). And an improvement of importance in the chain bridge is the construction by me of the timber. Communicated by James Kirby of having the uprights on each side so high that they are placed under the chain. And cause away the top of the uprights from the chain in the following manner. I place posts in each pair of large square timber so high only as to correspond with the posts in the other pairs or abutments and set them upon eight to ten feet in the massing of the pairs in boxes of planks or a solid stone or stone to be filled with timber & presence the posts in the chain. They rest with their bottom on the post. At the bottom they are to be connected by large bars of iron which is to be worked into the stone. Bars of iron or cast iron are to be fixed to the masonry work on the upper surface of the pairs for the purpose of receiving braces to support the posts. The posts are then to be except with a large pair of square timber over which the chains are to pass. In this case there is to be Grace chains to come upon the bottom of the pair in which they are to be connected, when the foundation is made and the main chains for the support of the bridge are also to be secured to the bottom of the pairs either to the timber on which the pairs rest or sufficiently secured in the masonry. If the water is salt or brackish, the chains must be made of Copper, & far as they go into the water, The use of many chains made of small iron divide the rest.

giving weather

and affords a better opportunity of detecting flaws.

of chains

Improved title by title to a great improvement in Chain Bridges.

an chain on a title and that made of large timbers is mentioned in my patent of the 16 of August 1805

and that the more iron is broken the better it is.

to the application to the support of bridges

they that have been thought

a rolling, twist or otherwise been reduced to flat and thin bars or strips

the bottom of which is made in the same manner with the flat bar chain except

that it is composed of small bars and strips. They are to be preserved from oxidation by

water and air or a copper covering.

or the implementer
